UNITED STATES PATENT OFFICE

HERMANN SCHULER AND ANTON GIETMANN, OF DUSSELDORF, GERMANY, ASSIGNORS
TO RHEINISCHE METALLWAAREN- UND MASCHINENFABRIK, OF DUSSELDORF-
DERENDORF, GERMANY, A CORPORATION OF GERMANY

BARREL-RECOIL GUN HAVING A FUSE-SETTING MACHINE

Application filed April 21, 1930, Serial No. 446,081, and in Germany August 26, 1927.

Barrel recoil guns having a fuse setting machine are known the driving mechanism for setting the fuse of which is driven by a power accumulator which is loaded by the kinetic energy of the gun barrel on firing.

5 In these guns, springs serve as power accumulators which are tensioned during a portion of the recoil of the barrel by a catch provided at the barrel, may extend again independently of the further movement of the 10 barrel and may then operate the fuse setting machine to set the fuse of a projectile by means of a rack engaging with a toothed wheel, coupled to the drive of the fuse setting machine during the rotation in one direction only.

In the known devices, the power accumulators are loaded directly by the mass of the recoiling barrel. The extremely high forces 20 of acceleration during the first part of the recoil of the barrel thereby unabatedly act, by means of the rigid intermediate gear, upon the power accumulator which considerably reduces the duration of life of these parts.

25 Moreover, it is impossible to regulate the loading and discharging of the power accumulator and its supply of power to the fuse setting machine according to time and height of power. To maintain the connection between the barrel and the power accumulator 30 for the drive of the fuse setting machine by means of the known rigid transfer of power, it is necessary to provide the power accumulator and the fuse setting machine at the

35 cradle of the barrel, so that, during elevations of the barrel, the cup-shaped setting bodies change their position and occupy at high elevations a position which makes it difficult to introduce a projectile.

40 The object of the present invention is to obviate these draw-backs by connecting the power accumulator for the drive of the fuse setting machine with the barrel by an intermediate gear which elastically transfers 45 the kinetic energy of the barrel to the fuse setting machine. This intermediate gear may be of a purely mechanical construction having springs and which may, if desired, be provided with an additional gear, particularly reducing the barrel acceleration and

having a ratio of gear which changes at running off. Preferably, however, the gear is formed as a pneumatic or pneumatic-hydraulic gear by tensioning the power carrier of the power accumulator, for instance a coiled spring, by compressed air or displaced liquid from an air compressor driven by the movements of the barrel. By simultaneously constructing the power accumulator for the drive of the fuse setting machine according to the invention as power accumulator of compressed air, it is possible to easily regulate the loading of the power accumulator and its supply of power to the fuse setting machine according to time and to height of power, so that, at the one hand, the effect of the ununiform barrel accelerations upon the power accumulator is obviated and the latter is loaded not by shocks or impulses but uniformly and, at the other hand, the driving mechanism of the fuse setting machine which is bound to definite numbers of revolutions and to definite periods is, as desired, moved smoothly and free of shocks. Moreover, the fuse setting machine together with its power accumulator for the drive are connected to fixed portions of the gun not participating in the elevation movements of the barrel and the power accumulator is connected to the barrel by means of a flexible gear.

In the accompanying drawings, several constructions of devices according to the invention are shown by way of example.

Fig. 1 shows a compressed air power accumulator for driving the fuse setting machine with a pneumatic-elastic connecting gear to the barrel of the gun; Fig. 2 is a diagrammatic view of the device mounted upon the gun seen from above and drawn at a smaller scale; Fig. 3 shows in section the connecting gear between the compressed air power accumulator and the barrel of the gun, formed as a pneumatic-hydraulic gear with energy tapping from the buffering and running out device of the barrel comprising a compressed air container; Fig. 4 is a sectional view of a further modification of the power accumulator for the drive of the fuse setting machine,

As will be seen from Figures 1 and 2, a conical torsion drum d is arranged between the barrel a of the gun and the power accumulator c for driving the fuse setting machine b by means of compressed air. The fuse setting machine b , the power accumulator c for driving the setting machine b and the drum d are provided at the carriage a_1 which does not participate in the elevation movements 10 of the barrel. During the recoil of the barrel, the drum d is rotated by a cable d_1 helically wound around the drum and fixed to the barrel of the gun. Under the action of a torsion spring, mounted within the drum casing, the 15 drum is, during the forward movement of the barrel rotated in the opposite direction and thereby the cable d_1 is wound again around the drum d . On account of the conical construction of the drum d , the barrel accelerating forces and the barrel velocities, changing 20 constantly during the recoil of the barrel, are correspondingly reduced and transferred, in a compensated state, to the intermediate gear connecting the power accumulator c to the drum d . The intermediate gear between the drum and the power accumulator is so constructed that it couples the power accumulator to the drum and loads same for a portion 25 of the barrel recoil only, but remains without influence upon the power accumulator during the rest of the recoil of the barrel. The intermediate gear may, for example, comprise a shaft d_2 coupled to the drum d , a worm gear d_3 , d_4 and a lever d_5 30 keyed to the shaft d_5 of the worm wheel. A tongue d_6 , mounted upon the pin d_7 of the lever d_6 so as to be capable of oscillating in one direction, is, during the rotation of the drum d at the recoil of the barrel, moved 35 from an original or exit position A into an end position B and shifts, during a portion of this movement, a rack c_1 of the power accumulator c . During the forward movement of the barrel and the hereby resulting 40 oscillation of the lever d_6 in the other direction, the tongue d_6 freely slides beneath the rack c_1 back into the original or exit position A. At the point at which the tongue d_6 presses upon the rack c_1 , a roller c_2 is 45 resiliently mounted on the rack c_1 which elastically absorbs the impulses of the tongue d_6 . Hereby the rack c_1 is, in the middle portion of the recoil of the barrel, displaced with 50 gradually increasing acceleration towards the right, whereby the roller c_2 rolls upon the end surface of the tongue d_6 until both parts come out of engagement. During the 55 further recoil and forward movement of the barrel, the power accumulator c is, therefore, 60 disengaged from the barrel.

The power accumulator c comprises a compressor space or chamber c_3 which is partly filled with liquid but which for its greatest part contains air. The compression chamber 65 c_3 is, by means of an opening c_4 of relatively

great cross section, connected to a chamber c_5 containing liquid. Movably arranged in the liquid chamber c_5 is a piston c_6 the piston rod c_7 of which extends through a stuffing box of the cylinder cover and is rigidly connected to the rack c_1 . In the state of rest of the power accumulator, the compressed air chamber c_3 and its opening c_4 are, by means of a spring loaded valve c_8 , closed against the liquid column c_5 in front of the piston c_6 . 70 The two chambers c_3 and c_5 are then connected by means of a channel c_9 only which may be throttled by a regulating member and has, with regard to the opening c_4 , a very small cross section. 75

By the movement of the rack c_1 resulting during a portion of the barrel recoil by means of the drum d and the lever d_6 , the compressor piston c_6 which is also moved presses the liquid in front of it through the opening c_4 into the compressed air chamber c_5 , thereby pushing back the valve c_8 . The result of this is, that the air is compressed and energy is stored. As soon as during the recoil of the barrel the tongue d_6 of the lever d_6 downwardly slides off the roller c_2 of the rack c_1 and therefore the piston c_6 comes to rest, the non-return valve c_8 is closed and the two chambers c_3 and c_5 communicate by the small adjustable bore c_9 only. The power accumulator now may discharge. The compressed air presses the liquid from the chamber c_3 , by way of the bore c_9 , back to the chamber c_5 and the piston c_6 and the rack c_1 are moved rearwardly to the left. The rack c_1 engages a toothed wheel c_9 , coupled to the driving gear b_1 , b_2 , b_3 , b_4 and b_5 of the fuse setting machine in such a manner, that it transfers to the driving gear of the fuse setting machine the rotation in one direction, i. e. in a counter-clockwise direction, only which rotation is imparted to the toothed wheel c_9 by the power accumulator during delivery of power and movement. During the movement of the rack c_1 to the right for loading the power accumulator, the toothed wheel c_9 runs idle. If the power accumulator c discharges, the fuse setting machine is started and its setting bodies, serving to set the fuse, are rotated in a well known manner. The period of discharge and the power delivery of the power accumulator c may be regulated by the throttling member arranged in the bore c_9 . 100

In the modification shown in Figure 3, the buffering and running out device e of the barrel is used as elastic element in the connecting gear between the barrel and the power accumulator. In this arrangement, a portion of the energy stored in the buffering and running out device e during the recoil of the barrel is tapped to load the above described power accumulator c . The buffering and running out device e comprises, as is well known, a cylinder filled with liquid which, during the recoil of the barrel, is, by means 110

of a piston, displaced into a compressed air container. For example, a portion of the liquid displaced in the cylinder is passed behind the piston c_6 of the power accumulator

- 5 c by means of a flexible hose or, when rigid pipes f are used, by way of the trunnion and an interconnected throttling member g . The piston c_6 is thereby shifted and the liquid in the chamber c_5 in front of the piston is 70 pressed into the compressed air chamber c_3 , so that the power accumulator is loaded. If the barrel is completely or nearly completely moved forwardly, the discharge of the power accumulator c and the drive of the 75 fuse setting machine are caused by the fact, that, by the compressed air in the compressed air chamber c_3 , the displaced liquid is pressed back again through the adjustable bore c_8 into the chamber c_5 , whereby the liquid in 80 front of the piston c_6 is pressed back into the buffering and running out device e .

As the pressures prevailing in the buffering and running out cylinder e at the end of the recoil and at the beginning of the forward 25 movement of the barrel are much higher than necessary for loading the power accumulator c , it is, by regulating at g the supply of liquid from the cylinder e to the power accumulator c , possible to so prolong the loading period of the power accumulator, that the loading 30 is continued, after the completion of the recoil of the barrel, during the forward movement of the latter. An unfavorable effect of the ununiform barrel movements upon the 35 power accumulator is thereby impossible and instead of being loaded by impulses, the power accumulator is nearly uniformly loaded. With this device also the discharge of the power accumulator occurs independently 40 of the barrel movement.

In the construction shown in Figure 4, a coiled spring h arranged in front of the piston c_6 serves as power carrier in the power accumulator. This spring h is tensioned by 45 energy tapped from the buffering and running out cylinder by the fact, that, as described above, the liquid of the buffering and running out cylinder is, during the recoil of the barrel, passed, by way of a throttling member g in the pipe f and a non-return valve i , behind the piston c_6 . During the discharge of 50 the power accumulator under release of the spring h the liquid is returned to the buffering and running out cylinder by way of a small 55 channel k in which a throttling member is arranged. The spring h is, therefore, not suddenly released but with regard to velocity and period of time in an adjustable ratio 60 adapted to the operation of the fuse setting machine.

What we claim is:

1. A recoil barrel gun having a fuse setting machine, comprising in combination a driving mechanism for setting a fuse, a power 65 accumulator loaded by the kinetic energy of the

gun barrel and serving to operate said driving mechanism and a gear connecting said power accumulator to said gun barrel, said gear being adapted to elastically transfer the kinetic energy of said barrel to said power 70 accumulator and to be adjusted according to time and height of power.

2. A recoil barrel gun according to claim 1 in which said connecting gear between said barrel and said power accumulator for the 75 drive of said fuse setting machine comprises a transmission gear, for instance a cable drive with a conical winding drum, adapted to reduce the barrel accelerations and having a transmission ratio which varies during running off.

3. A recoil barrel gun according to claim 1 in which a pneumatic connecting gear is provided between said gun barrel and said power 85 accumulator for driving said fuse setting machine, the power carrier of said power accumulator, for instance a coiled spring, being tensioned by compressed air from an air compressor operated by the barrel movements.

4. A recoil barrel gun according to claim 1 in which a pneumatic-hydraulic connecting gear is provided between said gun barrel and said power accumulator for driving said fuse setting machine, the power carrier of said power 90 accumulator, for instance a coiled spring, being tensioned by compressed air from an air compressor operated by the barrel movements.

5. A recoil barrel gun according to claim 1 in which a pneumatic connecting gear is provided between said gun barrel and said power 100 accumulator for driving said fuse setting machine, the power carrier of said power accumulator, for instance a coiled spring, being tensioned by displaced liquid from an air 105 compressor operated by the barrel movements.

6. A recoil barrel gun according to claim 1 in which a pneumatic-hydraulic connecting gear is provided between said gun barrel and said power 110 accumulator for driving said fuse setting machine, the power carrier of said power accumulator, for instance a coiled spring, being tensioned by displaced liquid from an air compressor operated by the barrel 115 movements.

7. A recoil barrel gun according to claim 1 in which a pneumatic connecting gear is provided between said gun barrel and said power 120 accumulator for driving said fuse setting machine, the power carrier of said power accumulator, for instance a coiled spring, being tensioned by compressed air from the buffering and running out device of said gun barrel.

8. A recoil barrel gun according to claim 1 in which a pneumatic-hydraulic connecting gear is provided between said gun barrel and said power accumulator for driving said fuse setting machine, the power carrier of said power 125 accumulator, for instance a coiled

spring, being tensioned by compressed air from the buffing and running out device of said gun barrel.

9. A recoil barrel gun according to claim 1 in which a pneumatic connecting gear is provided between said gun barrel and said power accumulator for driving said fuse setting machine, the power carrier of said power accumulator, for instance a coiled spring, being tensioned by displaced liquid from the buffing and running out device of said gun barrel.

10. A recoil barrel gun according to claim 1 in which a throttling member is provided in an admission channel leading from an air compressor, mounted on said gun barrel, to said power accumulator of said fuse setting machine and a second throttling member is provided in a return channel from said power accumulator to said air compressor, said throttling members allowing a regulation of the loading and discharging of said power accumulator according to time and to reception of power as well as delivery of power to said fuse setting machine.

11. A recoil barrel gun according to claim 1 in which the said power accumulator for the drive of said fuse setting machine is formed as a compressed air power accumulator having a liquid filled displacer cylinder and a piston reciprocating in same, the liquid from said cylinder being, for the purpose of loading said power accumulator, pressed through a large opening into a compressed air container in which, for the purpose of delivering power to said fuse setting machine, said displaced liquid is, under the action of the compressed air, pressed back again through a small opening adapted to be throttled.

12. A recoil barrel gun according to claim 1 in which said fuse setting machine and said power accumulator for operating said machine are mounted at fixed parts of the gun, not participating in the elevation movements of said barrel, said power accumulator being connected to said barrel by a flexible gear adapted to transmit power and movement.

In testimony whereof we have affixed our signatures.
